UNITED STATES PATENT OFFICE.

AUGUST WEBER, OF NEWARK, NEW JERSEY.

IMPROVEMENT IN CASTER-BOTTLES.

Specification forming part of Letters Patent No. **140,564**, dated July 1, 1873; application filed May 14, 1873.

To all whom it may concern:

Be it known that I, AUGUST WEBER, of Newark, in the county of Essex and State of New Jersey, have invented Improvement in Bottles for Sauces, &c., of which the following is a specification:

The object of this invention is to exclude the sauce or other liquid contents from the atmosphere, and allow for the ejecting of a small quantity at a time upon food or other substances. I make use of a bottle to hold the liquid, and at one end thereof is a screw-cap with a plunger-rod passing through it, and at the other end is a nipple and cylinder. The plunger acting in the cylinder ejects more or less liquid through the nipple.

In the drawing I have shown the said bottle by a vertical section.

The bottle *a* is made with a neck, receiving the collar *b*, that is provided with a screw that receives the cap *c*, and an elastic washer renders the joint water-tight. Through the cap *c* a rod, *d*, passes, that is provided with a head, *e*, at the upper end and a piston, *k*, at the lower end. A spring, *i*, serves to lift this rod *d* and piston *k* and confine an elastic washer, *l*, between the cap *c* and a collar, *o*, upon the rod *d* so as to make the joint between the rod *d* and cap *c* tight. At the lower end of the bottle *a* is an opening receiving the nipple *r* and its cylinder *s*. These

usually will be of hard rubber, and retained in place by a nut and elastic washer.

It will now be understood that when a liquid is poured into the bottle *a* the nipple *r* may be kept closed by the finger until the cap *c* has been screwed on air-tight, and then the liquid will be retained by the atmospheric action. When the sauce or other liquid is to be ejected the rod *d* is to be pressed upon to drive the piston *k* into the cylinder *s*, and in this manner any desired quantity of the sauce or other liquid can be delivered in a small jet. The piston and rod being drawn back by the spring *i* produces a sufficient exhausting action to prevent the liquid dropping from the nipple *r*.

The shape of the bottle *a* may be varied according to the use to which the liquid is to be put, and a saucer may be provided for the bottle to stand in, or the bottle may be inverted in the stand when used as a caster.

I claim as my invention—

The bottle *a*, screw-cap *c*, rod *d*, spring *i* and piston *k*, in combination with the cylinder *s* and nipple *r*, as and for the purposes set forth.

Signed by me this 8th day of May, 1873.

AUGUST WEBER.
